UNITED STATES PATENT OFFICE.

JOHN L. HUGHES, OF TULSA, OKLAHOMA, ASSIGNOR OF ONE-HALF TO ELBERT N. WYCOFF, OF TULSA, OKLAHOMA.

COMBINATION TOOL.

Application filed July 23, 1921. Serial No. 487,150.

To all whom it may concern:

Be it known that I, JOHN L. HUGHES, a citizen of the United States, residing at Tulsa, in the county of Tulsa and State of Oklahoma, have invented certain new and useful Improvements in Combination Tools, of which the following is a specification.

This invention has as its object to provide an improved combination tool for use by carpenters and builders, and the primary object of the invention is to provide a tool which may be conveniently employed in marking off weather boarding so that the same may be accurately cut to the required length without the necessity of following the tedious method of procedure heretofore practiced.

More specifically, the invention contemplates the provision of a tool adapted for application to a weather board and to serve as a straight edge along which a pencil may be drawn to indicate where the board is to be cut off in order to fit it into place, the tool embodying means for abutment against the frame of a window or door against which the weather board, is temporarily laid, and thus indicate the required length of the board.

Another object of the invention is to provide a combination tool which, in addition to its use as above indicated, may be employed as a try-square and also as a scribe, so that the tool will prove generally useful to the workman employing the same.

In the accompanying drawing:

Figure 1 is a view in elevation of the tool embodying the present invention, the view illustrating the manner in which the tool is to be employed in marking off a weather board.

Figure 2 is an edge elevation of the tool.

Figure 3 is a view similar to Figure 1 disclosing a tool marked with a modified form of scale and illustrating the manner in which the tool is to be employed in scribing circles.

The tool embodying the invention comprises a stock 1 which has perfectly flat faces and straight parallel lateral edges indicated by the numeral 2. The stock 1 is preferably formed from a length of bar metal which has its opposite end portions bent at right angles to the plane of the stock to provide abutment flanges indicated by the numeral 3, the lateral edges of these flanges

being in the planes of the corresponding lateral edges of the stock. As a matter of convenience, the stock may be provided adjacent each lateral edge with a scale 4 in inches and fractions of inches. The scale may be the one shown in Figure 1 or a modified form of scale such as shown in Figure 3.

Both of the flanges 3 project from the same side of the stock 1, and in the use of the tool, for example in marking off a weather board previous to cutting the board to the required length and nailing it in place, the weather board which is indicated by the letter W in Figure 1 is temporarily disposed in the position which it will eventually occupy and with one end, which is to be cut off, extending over the face of the door or window frame which has been encountered in the course of construction, this frame being indicated by the reference letter D. The tool is then disposed flat against the outer face of the weather board with one of the other of its flanges 3 engaging squarely over the upper or lower edge of the board, as the case may be, and the tool is slid along the board until the lateral edges of both of its said flanges abut against the adjacent side or edge of the door or window frame. A pencil may then be drawn along that lateral edge 2 of the stock which is presented next to the said frame, thus indicating the precise point at which the weather board is to be cut off in order to adapt it to fit exactly into place.

It will be understood that when the tool is to be made use of as a try-square, it will be employed in substantially the manner recited above. That is to say it will be disposed against the piece of material to be marked off and with one of its flanges 3 resting against an edge of the material. It is to be understood of course that the flanges 3 will extend exactly at right angles to the lateral edges of the stock 1 so that each lateral edge of the stock will occupy a position at right angles to the plane of either flange.

In order that the tool may be employed as a scribe, it is provided with a pair of compasses the legs of which are indicated by the numeral 5, these legs being pivotally mounted at their inner ends upon a threaded stud 6 which is secured to the stock 1 and projects from that face of the stock opposite the face from which the

flanges 3 project. A wing nut 7 is threaded on to the stud 6 and may be tightened to bind the pivoted inner ends of the compass legs 5 so as to secure the said legs in positions of adjustment. By loosening the nut 7, the compass legs may be swung together and pivoted about the stud 6 so as to occupy for example the position shown in Figure 1 of the drawing in which position the compass attachment will lie wholly within the bounds of the margin of the stock 1. When the attachment is to be made use of, the nut 7 may be again loosened and the legs 5 may then be swung about the stud 6 so that their scribing ends will extend beyond the adjacent end of the stock as illustrated in Figure 3 of the drawing, it being understood that after the compass legs have been relatively adjusted, the nut 7 is to be tightened so as to bind them in place whereupon the tool may be employed in scribing circles by grasping the stock 1 and utilizing this portion of the tool as a handle.

Having thus described the invention what is claimed as new is:

A tool of the character described com-

prising a gage member formed from an elongated strip of flat metal of an even width throughout its length to provide straight parallel side edges, side strips being bent transversely in spaced relation to its ends and having its bent end portions extending from one face of the intermediate portion of the strip at right angles thereto, the outer face of the intermediate portion of said strip being provided with gage markings, said gage markings being disposed transversely thereon and in measuring relation to the inner face of one of the bent end portions, a threaded stud extending from the outer face of said strip intermediate the width thereof and adjacent one end of the intermediate portion, a pair of sharp pointed compass legs pivoted on said stud for swinging movement from an inoperative position within the confines of the outer face of the intermediate portion of said strip to an extended operative position, and a nut upon said stud adapted to clamp said legs in adjusted positions.

In testimony whereof I affix my signature.

JOHN L. HUGHES. [L. S.]
